UNITED STATES PATENT OFFICE.

ARTHUR A. AMBLER, OF MIDDLETOWN, OHIO, ASSIGNOR TO THE AMERICAN ROLLING MILL CO., OF NEWARK, NEW JERSEY.

NESTING CULVERT.

1,082,578.

Specification of Letters Patent. Patented Dec. 30, 1913.

Application filed September 6, 1913. Serial No. 788,395.

To all whom it may concern:

Be it known that I, ARTHUR A. AMBLER, a citizen of the United States, residing at Middletown, Butler county, Ohio, have invented certain new and useful Improvements in Nesting Culverts, of which the following is a specification.

This invention pertains to that class of sheet metal culverts formed of separate sections united to each other on circumferential and longitudinal lines, the sections being originally separate from each other so that they may be nested for storage and shipment, joint devices being provided for securing the sections together.

The present invention will be readily understood from the following description taken in connection with the accompanying drawings in which:

Figure 1 is a side elevation of several sections or parts of sections associated and united: Fig. 2 a plan of one of the sections in association with one of its endwise neighboring sections, together with one of the longitudinal joint-pieces: Fig. 3 a transverse section of the culvert: and Fig. 4, a longitudinal section of a portion of the joint-piece.

In the drawings:—1, indicates one of the culvert-sections, semicircular in cross-section, in the illustrated example, the section being formed of sheet metal circumferentially corrugated, the section being illustrated in Fig. 1 as being at the top of the culvert; 2, a second similar section at the top of the culvert, the contiguous ends of the two sections of half-culvert adjoining by having the end of one section overlapping the end of the contiguous section sufficiently to enable the first corrugations on the ends of the sections to engage each other: 3, one of the bottom sections of the culvert, similar to the top section and to be similarly arranged in a longitudinal series, with their ends similarly united by overlapping corrugations, the longitudinal edges of the half culvert represented by the upper sections resting over but not in contact with the upper edges of the lower half culvert:

4, the space extending longitudinally between the contiguous edges of the upper and lower half culverts: 5, a transversely corrugated cover-strip disposed upon the interior of the culvert and covering the joint between the upper and lower sections, this

cover-strip being preferably about the length of one of the culvert sections and there being a sufficient number of them to cover the entire open joint 4 between the upper and lower half culvert sections: 6, a similar transversely corrugated cover-strip disposed at the outside of the joint between the upper and lower half culvert sections: 7, rivets uniting the inner and outer cover-strips: 8, spacing pieces between the inner and outer cover-strips, formed, in the present instance, by shoulders on the rivets between the two cover-strips, so as to form upper and lower grooves in the upper and lower edges of the composite cover-strips: 9, the overlapping ends of the sections at the end-joints between sections.

Sheet metal culverts are made in sizes varying from six inches to six feet in diameter. In the illustration the complete circle of the culvert is formed by two semicircular halves united by two diametrically opposite longitudinal joints, but it is to be understood that in the larger sizes of culverts it may be desirable to form the circle of the culvert in more than two parts and to employ a correspondingly greater number of longitudinal joints. Culverts of this character are generally constructed with their sections two or three feet long.

It is to be observed that at the ends of the composite cover-strips, formed by the cover-strips 5 and 6, the end of one member projects endwise beyond the other member, and also that the outer member is narrower than the inner member. The composite cover-strips are, preferably, about the length of the culvert-sections.

The individual culvert-sections may be nested, and the cover-strips pertaining to the nesting of sections may be laid within the nest of sections, thus providing for compactness in storage and shipping. The grooves formed in the upper and lower edges of the composite cover-strips, by means of the spacing-pieces 8, are of sufficient width to admit the longitudinal joint edges of the sections without requiring very considerable force.

In erecting the culvert for use, the lower sections are arranged in line, preferably *in situ*, with their contiguous ends overlapping, a sufficient number of sections being employed to produce the desired total length of culvert, one or more fractional lengths

being employed if necessary in securing the desired total length.

Composite cover-strips in sufficient number are then to have their lower grooves applied over the upper edges of the lower half culvert, with the cover-strips breaking joint with the lower sections, and fractional cover-strips being employed if needed. The upper sections are then to be applied, with their contiguous ends overlapping and with their end joints breaking joint with the end joints of the lower culvert section and with the joints of the cover-strips, the lower edges of the upper sections engaging down in the grooves of the cover-strips. One or more fractional top culvert sections may be employed if needful in securing proper lengths and the matching of ends with the lower half-culvert.

20 In applying the composite cover-strips to the upper edges of the lower sections, the superior width of one of the members of each strip permits of a positioning and steering operation, not possible if both members of the composite strip were of the same width, also, does the projection of the end of a member of the composite cover-strip facilitate the positioning, not only of the top culvert sections but of the endwise contiguous cover-strips. It is preferred to give to the inside cover-strips a transverse curvature of greater radius than the curvature of the culvert sections, but the outside cover-strips may be transversely flat, this construction resulting in the upper and lower grooves in the cover-strips being wider at their outer extremities than down at the rivets, thus providing the grooves with entering throats for the edges of the culvert sections. The grooved cover-strips when formed of inner and outer components, as in the illustration, may have those components spaced apart to form the grooves by any suitable means, such as enlarged bodies 45 on the rivets, or washers on the rivets between the outer and inner members of the composite cover-strips. Owing to the fact that the upper culvert-sections break joint with the lower culvert-sections and that the 50 contiguous ends of the composite cover-strips are in overlapping arrangement, the space 4 between contiguous horizontal edges of the culvert-sections is not objectionable, and the presence of this space bringing 55 about the saving of a certain degree of metal in the formation of the culvert, and it is more economical than would be the providing of the longitudinal edges over the culvert-sections with notches to straddle the 60 rivets.

Giving consideration to one of the composite cover-strips in Fig. 3 it will be observed that the grooves are wider than the thickness of the metal of the culvert-sections so that the gripping of the cover-strip

upon the edges of the culvert-sections is not effected by direct frictional fitting or pinching, but that the curved metal at the edge of the culvert-sheet acts in a lever-like manner in the groove, this system giving ample 70 stability to the joint when formed and at the same time facilitating the association of the sections and cover-strips, the resiliency of the sections permitting the edges of the sections to be freely inserted in the 75 grooves of the cover-strips.

I claim:—

1. A nesting culvert comprising, a plurality of curved sheet-metal culvert-sections arranged in circumferential series with their longitudinal edges near each other, and cover-strips adapted to cover the inner and outer surfaces of the edges of the sections and having grooves in their opposite edges adapted to engage the edges of the culvert-sections, that portion of each cover-strip which engages within the culvert having a width differing from that portion engaging outside the culvert, combined substantially as set forth. 80

2. A nesting culvert comprising, a plurality of curved sheet-metal culvert-sections arranged in circumferential series with their longitudinal edges near each other, and cover-strips adapted to cover the inner and outer surfaces of the edges of the sections and having grooves in their opposite edges adapted to engage the edges of the culvert-sections, that portion of each cover-strip engaging inside the culvert being wider than 85 the portion engaging outside of the culvert, combined substantially as set forth. 90

3. A nesting culvert comprising, a plurality of curved sheet-metal culvert-sections arranged in circumferential series with their longitudinal edges near each other, and cover-strips adapted to cover the inner and outer surfaces of the edges of the sections and having grooves in their opposite edges adapted to engage the edges of the culvert-sections, the end of each cover-strip where it engages the interior of the culvert having a projection beyond the same end of the cover-strip engaging the exterior of the culvert, combined substantially as set forth. 105

4. A nesting culvert comprising, curved sections with their longitudinal edges near each other, a cover-strip adapted to cover the inner surface of the longitudinal edges of the sections, a cover-strip adapted to cover the outer surface of the longitudinal edges of the sections, rivets securing the two cover-strips together, and spacing pieces at the rivets between the 110 cover-strips to space them apart sufficiently to admit the edges of the culvert-sections, combined substantially as set forth. 120

5. A nesting culvert comprising, a plurality of curved sheet-metal culvert-sections 125

arranged in circumferential series with their longitudinal edges near each other, and cover-strips adapted to cover the inner and outer surfaces of the edges of the sections 5 and having grooves in their opposite edges adapted to engage the edges of the culvert-sections, said grooves being provided with entering throats to facilitate the entry of the longitudinal edges of the culvert-sections, combined substantially as set forth.

6. A nesting culvert comprising, curved sheet-metal sections to be coupled at their longitudinal edges, a sheet-metal cover-strip engaging the inner surfaces of contiguous 15 edges of the sections and transversely curved to fit the edges of the sections, a flat cover-strip adapted to engage the outer surfaces of contiguous edges of the sections, and means connecting the two cover-strips together but 20 separated from each other and passing from the outside to the inside of the culvert, combined substantially as set forth.

7. A nesting culvert comprising, curved circumferentially corrugated sheet-metal sections to be coupled at their longitudinal 25 edges, a transversely corrugated sheet-metal cover-strip engaging the inner surfaces of contiguous edges of the sections and transversely curved to fit the edges of the sections, 30 a transversely corrugated flat cover-strip adapted to engage the outer surfaces of contiguous edges of the sections, and means connecting the two cover-strips together but separated from each other and passing from 35 the outside to the inside of the culvert, combined substantially as set forth.

8. A composite joint-strip for circumferentially corrugated culvert sections comprising, a sheet-metal cover-strip transversely 40 corrugated to fit the interior of the culvert-sections, a sheet-metal cover-strip transversely corrugated to fit the exterior of the

culvert-sections, rivets uniting the two cover-strips, and spacing-pieces disposed between the two cover-strips at the rivets to space the 45 cover-strips apart sufficiently to receive the edges of the culvert-sections, combined substantially as set forth.

9. A composite joint-strip for circumferentially corrugated culvert-sections comprising, a sheet-metal cover-strip transversely corrugated to fit the interior of the culvert-sections, a sheet-metal cover-strip transversely corrugated to fit the exterior of the 50 culvert-sections, rivets uniting the two cover-strips, and spacing-pieces disposed between the two cover-strips at the rivets to space the cover-strips apart sufficiently to receive the edges of the culvert-sections, the two cover-strips being of dissimilar width and each cover-strip having an end projecting beyond the end of the other cover-strip, combined substantially as set forth.

10. A nesting culvert comprising, a plurality of curved sheet-metal culvert-sections 55 arranged in circumferential series with their longitudinal edges near each other, and cover-strips adapted to cover the inner and outer surfaces of the edges of the sections and having grooves in their opposite edges 60 adapted to engage the edges of the culvert-sections, the grooves in the edges of the cover-strips being wider than the metal of the edges of the culvert-sections to such extent that the extreme edges of the culvert-section, when in place will, impinge outwardly upon the base of the groove and a point farther removed from the edge will 65 impinge inwardly at the outer portion of the groove, combined substantially as set forth.
